UNITED STATES PATENT OFFICE.

WALTER HOLLAND, OF WASHINGTON, DISTRICT OF COLUMBIA, ASSIGNOR TO THE DOLLAR TRUST, OF WASHINGTON, DISTRICT OF COLUMBIA.

VACUUM HOLDING OR LIFTING DEVICE.

Application filed February 2, 1921. Serial No. 441,963.

To all whom it may concern:

Be it known that WALTER HOLLAND, who is a citizen of the United States, residing at Washington, in the District of Columbia, has invented certain new and useful Improvements in a Vacuum Holding or Lifting Device, of which the following is a specification.

My invention relates to improvements in 10 vacuums, and the object is to provide a hollow metallic container, of any shape, having a resilient member covering the opening which provides a vacuum chamber with a self-resisting portion, so that it may be employed as an ordinary vacuum, as well as 15 a holding device, lifting magnet, power device and as many other specific applications of the principle as may be desired.

A further object of my invention is to provide 20 a device comprising a vacuum so constructed that the same will maintain its position wherever placed. For the purpose of those familiar with devices of this character it is estimated that ordinary air exerts a 25 pressure of 14.69 pounds to the square inch of exposed surface, and the resilient portion of the container, yielding under the pressure of the outside air becomes tensed or stretched, and holds the container down 30 with a like pressure.

A still further object of the invention is the 35 simplicity in the construction and the decreased cost of manufacture which, together with the importance of a device of this character makes the same valuable in any commercial enterprise.

With the above and other objects in view, as will be hereinafter apparent, the invention 40 consists in general of certain novel and important features, hereinafter fully described, illustrated in the accompanying drawings, and the appended claims.

In the accompanying drawings, like characters of reference indicate like parts in the 45 several views of which;

Figure 1 is a vertical sectional view of the improved device,

Fig. 2 is a top plan view of the same,

Fig. 3 is a modification, showing the same 50 in section,

Fig. 4 is a detailed sectional view of the valve,

Fig. 5 is a top plan view of the disk 6 shown in Fig. 3.

Generally speaking my device consists of

a container 1, of any configuration, being of a rigid material and capable of withstanding the atmospheric pressure. This container so constructed is provided at its lower extremity with an opening 2, over which is placed a resilient material 3. This resilient material being fastened to the rigid member by any suitable fastening means which will cause the same to be air tight. This fastening means being illustrated in the drawing, by a circular band 4, which holds the resilient material in an air tight position against the extremity of the rigid member.

The rigid container is provided with a one-way valve 5, preferably at its upper extremity, this valve, however, being of any common construction, there being no claim made to the valve construction. It can be, if so desired, to have the valve placed in the resilient member which will have the same effect as if the same was placed in the upper extremity of the rigid container.

It is requisite that the resilient member be of such material or construction that the same will have sufficient resistance to sustain the normal weight of itself and the rigid member, as well as being sufficiently resilient so as to yield under the atmospheric pressure.

As disclosed in my modified form of construction, it will be apparent that the rigid container 1, is of the same construction as specified in Figure 1, and that the resilient member 3, is provided with an auxiliary resisting disk 6. This resisting disk 6 is provided with suitable holes 8, for the reception of springs 7. The springs 7 are connected at the other end to the rigid member 1, by any suitable means. This disk through the springs 7 which are connected to the rigid member 1 is sufficiently strong so as to sustain the normal weight of the rigid member and itself as well as yielding under the atmospheric pressure.

To more clearly illustrate my invention 100 the mode of operation is as follows:

Through the medium of a pump, not shown, the air within the container 1 is withdrawn through valve 5, thus creating a vacuum within said container. By creating 105 a vacuum within the container 1, the resilient member 3, is forced to a certain extent into the opening 2, as disclosed in dotted lines in Fig. 1. The exerted pressure upon the resilient member 3, is transmitted by the 110

2
 resilient member to the rigid container 1 which gives it a lifting or holding power equivalent to the amount of pressure exerted upon the resilient member by the atmosphere attempting to force its way into the rigid container 1.

Having thus described my invention, what I claim as new is:

1. A vacuum head, comprising a rigid hollow receptacle having an open mouth, a resilient member over and closing the open mouth of said rigid receptacle to provide an air tight chamber, the receptacle being provided with means to facilitate connection of a pump therewith to exhaust air from said receptacle, said resilient member being constructed and adapted to be flexed into the mouth of the rigid receptacle from normal condition by the atmospheric pressure there against upon the exhaustion of air from said chamber and means to prevent return of air into the receptacle.

2. A vacuum head, comprising a rigid hollow receptacle having an open mouth, a resilient member over and closing the open mouth of said rigid receptacle to provide an air tight chamber, and a valve carried by the receptacle provided with means to facilitate connection with the pump therewith to exhaust air from said receptacle, said resilient member being constructed and adapted to be flexed into the mouth of the rigid receptacle from normal condition by atmospheric pressure there against upon the exhaustion of air from said chamber, said

valve preventing return of air into the receptacle.

3. A vacuum head, like that described in claim 1, wherein the resilient member is provided with an auxiliary resisting disk, said disk being located in spaced relation to and parallel with the resilient member inwardly of the latter and radial elastic members having their ends respectively connected to the rigid member and the marginal portions of the auxiliary resisting disk for yieldingly supporting the latter substantially centrally of the resilient member.

4. A vacuum head like that described in claim 1, wherein yieldable means is provided inwardly of and adjacent to the resilient member for providing auxiliary resistance to the flexing of the resilient member.

5. A vacuum head, comprising a rigid hollow receptacle having an open mouth, a resilient member over and closing the open mouth of said rigid receptacle to provide an air tight chamber, the receptacle being provided with means to facilitate exhaustion of air therefrom, said resilient member being constructed and adapted to be flexed into the mouth of the rigid receptacle from normal conditions by the atmospheric pressure there against upon the exhaustion of air from said chamber, and means to prevent return of air into the receptacle.

In testimony whereof I hereunto affix my signature.

WALTER HOLLAND.
